UNITED STATES PATENT OFFICE

GEORGE A. VAUGHN, OF NEWTON, IOWA, ASSIGNOR TO THE PARSONS COMPANY, OF NEWTON, IOWA, A CORPORATION OF IOWA

EXCAVATOR CHAIN CONSTRUCTION

Application filed May 28, 1930, Serial No. 456,569. Renewed December 1, 1932.

The object of my invention is to provide an excavator chain consisting of a series of like elements pivoted together whereby a link chain, digging and conveying buckets and cleaners for the buckets are formed by the series of elements thus connected with each other, each element being of simple, durable and inexpensive construction.

A further object is to provide an excavator chain consisting of elements pivoted together for forming an endless digging chain, each element having portions of a bucket formed thereon, such portions consisting of sides and a bottom for a bucket and a back which is adapted to cooperate with the sides and bottom of the next following bucket to form a back therefor, thus making it possible to closely space the digging buckets whereby in operation they resemble a milling cutter in which each cutting element takes a small portion of a cut and thus the cuts are divided between each link of the digging chain so that large cuts do not have to be taken in order to maintain a desired capacity for the digging and conveying excavator chain.

Another object is to provide stop shoulders on the inside surfaces of the sides of one bucket for the back member on the next bucket head to engage to prevent undesirable bowing of the chain under the stress of digging.

Another object is to provide an excavator chain consisting of a series of similar elements so arranged that when the elements pivotally travel over a sprocket wheel, all material from the buckets formed on the elements will be effectively discharged from the digging chain.

Another object is to form the bottom of each bucket element on a radius from the forward pivotal connection of the bucket whereby the back member for the bucket, when the chain travels over the sprocket, will sweep across such curved bottom of the bucket for both discharging material and cleaning the bucket bottom, the back being of such width and being positioned between the sides of the bucket whereby it also cleans them during the discharging operation.

A further object is to provide a unitary

element forming a link for an excavator chain and having buckets and cleaners provided in the proper relation to each other when a plurality of the elements are pivoted together by link pins for forming a complete excavator chain.

With these and other objects in view my invention consists in the construction, arrangement and combination of the various parts of my device, whereby the objects contemplated are attained, as hereinafter more fully set forth, pointed out in my claims and illustrated in the accompanying drawings. Although the invention is susceptible of a variety of embodiments, it is unnecessary to fully describe and illustrate more than one in order to give a full understanding of the invention both from its structural and functional standpoints. Accordingly, I have illustrated a preferred and desirable embodiment of the invention in the accompanying drawings in which:

Figure 1 is a side elevation of an excavator machine adapted for digging ditches and illustrating a combination chain, bucket and cleaner construction embodying my invention.

Figure 2 is a plan view of one of the buckets as viewed in the direction of the arrow 2 on Figure 1.

Figure 3 is a back elevation of one of the excavator chain elements looking in the direction of the arrow 3 on Figure 1 and showing in dotted lines the relative positions of the forward and rearward chain element in dotted lines.

Figure 4 is a vertical central sectional view through a series of the elements pivoted together to form an excavator chain and showing the elements traveling over an upper drive sprocket.

Figures 5, 6 and 7 are detailed sectional views on an enlarged scale on the lines 5-5, 6-6 and 7-7 respectively of Figure 4 and

Figure 8 is an enlarged sectional view of the portion of Figure 4 appearing in the circle 8.

On the accompanying drawings, I have used the reference numeral 10 to indicate generally the frame of an excavator or ditch

digging machine. Caterpillar treads 12 are provided on sprockets 14 for supporting the frame 10.

An excavator boom 16 is pivotally mounted 5 on a drive shaft 18 and carries the excavator chain, indicated generally by the reference character A.

The drive shaft 18 may be driven in any suitable manner from a motor 20 whereby 10 to operate the excavator chain A. The boom 16 may be raised and lowered, as desired, for adjusting the depth of a ditch 22 being dug by the excavator chain A by means of a chain 24 which may be actuated in either direction 15 as desired from a power shaft 26. The excavator chain A is adapted to dig the ditch 22 and discharge the diggings into a chute 28 and onto a laterally extending conveyor 30.

The excavator chain A consists of a series 20 of similar bucket or link elements, one of which I will now describe in detail. Each bucket or link element consists of a pair of side plates 32, a bucket bottom 34 and a bucket back 36. The bucket bottom 34 is reinforced 25 by ribs 35. The side plates 32 are provided at their forward back edges with bosses 38 adapted to receive a link pin 40. A tapered pin 42 or a bolt may be extended through one 30 of the bosses 38 and through the link pin 40 as shown in Figure 3 for holding the pin in position.

A hub 44 is formed on the inside of each side plate 32 adjacent their lower back edges. The total length of the hub 44 is slightly less 35 than the distance between the bosses 38. The hub 44 is bored out to rockably receive the link pin 40.

The forward edge of each side plate 32 is 40 enlarged and sharpened as indicated at 46 to aid in cutting the sides of the ditch 22.

The bottom member 34 of the bucket element has an inner surface formed on a radius from the center of the bosses 38, the purpose 45 of which will be hereinafter apparent. A downward bulge 48 is provided adjacent the lateral center of the bottom member 34 of the bucket whereby a flat surface for the inside of a digging blade 50 to engage is provided. A cross bar 52 is formed between the 50 sides 32 of the bucket element to engage the outside surface of the digger blade 50 whereby the digging strain on the blade is imparted to the cross bar 52. The ribs 35 besides reinforcing the bucket bottom 34 also 55 reinforce the cross bar 52.

As shown in Figure 6, the digging blade 50 has shoulders 54 and 56 engaging similarly shaped socket bottoms 58 and 60 formed in the bottom member 34 (see Figure 6). For 60 holding the digger blade 50 in position, I provide a bolt 62, the head of which is held in a socket 64 formed in the bulge 48. The bolt 62 extends through a portion 51 of the digger blade 50 formed rearwardly of the shoulder 65 56 and which fits between the sides of a slot

53 formed in the bucket bottom 34. A nut 66 is threaded on the bolt 62. The bucket back 36 extends downwardly from the bucket bottom 34 and the hub 44, the distance between the side edges 70 of which is slightly less than the distance between the inner surfaces of the bucket sides 32.

The dimension between the center of the hub 44 and the bottom edge 72 of the bucket back 36 is slightly less than the distance between the center of the bosses 38 and the top inner surface of the bucket bottom 34.

A series of the bucket or link elements just described are pivoted together by the link pins 40, as shown in Figures 1 and 5, their relative positions being shown by full and dotted lines in Figure 3 whereby a combination excavator chain and digging buckets is provided whereby the elements and pins solely constitute a digging chain. When a series of the bucket and link elements are thus assembled together, the side plates 32, bosses 38, hubs 44 and link pins 40 constitute a link chain while the side plates 32, bucket bottoms 34, bucket backs 36, sharpened edges 46 and digging blades 50 constitute digging and conveying buckets, the back 36 of one element serving as a bucket bottom 34 of the next following bucket element.

The particular arrangement of the similar elements provides a digging chain in which the cutters are close together and one, which due to the cooperation of the sides 70, their lower edge 72 of the bucket back 36 with the side plates 32 and the bucket bottom 34 of the next following bucket element provide for both the conveying and discharge of material dug by the excavator chain.

The discharge of the material is accomplished by the travel of the excavator chain over a drive sprocket 74, as best shown in Figure 4. The drive sprocket 74 has teeth 76 which engage the hubs 44 for driving the chain and in passing over the sprocket, the links of the chain pivot with respect to each other whereby the backs 36 swing outwardly, as indicated by the arrow 78, for discharging the material that has been dug and conveyed by the buckets and dropping it into the chute 28 onto the conveyor 30.

The side edges 70 and the bottom edge 72 of the bucket back 36 swing close to the bucket sides 32 and the bucket bottom 34 to act as a cleaner for the bucket as well as a discharging device. The bucket back 36 is reinforced by ribs 71 extending to the hub 44.

Stop shoulders 80 are formed on the inner surfaces of the side plates 32 for the lower corners of the bucket back 36 to rest against when the chain is traveling in a straight line. The coaction between the bucket backs 36 and the stop shoulders 80 prevents any undesired bowing of the digging stretch of the chain between the drive sprocket 74 and the idler sprocket 82 on the lower end of the boom 16.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

- 10 1. In a device of the class described, an excavator chain comprising links, each link comprising side walls perforated to receive link pins, said walls forming the sides of a bucket, a bottom for said bucket, a back wall 15 extending downwardly from the bottom of the bucket for forming a back for the next following bucket and link pins for pivoting said links together and means on each link for the back wall of the next forward bucket 20 to engage with to prevent flexing of the excavator chain in one direction.

75

- 25 2. In a device of the class described, an excavator chain comprising links, each link comprising side walls perforated to receive link pins, said walls forming the sides of a bucket, a bottom for said bucket, a back wall extending downwardly from the bottom of the bucket for forming a back for the next following bucket and link pins for pivoting 30 said links together, each link having a shoulder for the back wall of the next forward bucket to engage with to prevent flexing of the chain in one direction.

80

- 35 3. In a device of the class described, an excavator chain comprising links, each link comprising side walls perforated to receive link pins, said walls forming the sides of a bucket, a bottom for said bucket, a back wall extending downwardly from the bottom 40 of the bucket for forming a back for the next following bucket and link pins for pivoting said links together, each link having shoulders for the back wall of the next forward bucket to engage with to prevent flexing of 45 the chain in one direction, said shoulders being located between said side walls and spaced from each other for allowing the discharge of impacted material.

85

- 45 4. An excavator chain comprising a series 50 of elements each including bucket side plates, a bucket bottom and a bucket back and means for pivoting said side plates together whereby the bucket back of one element forms a back for the bucket side plates and bucket bottom of the following element, the bucket side plates of each element having stop shoulders thereon for the bucket back of the next forward bucket to engage against.

90

- 55 5. An excavator chain comprising a series 60 of elements, each including bucket side plates, a bucket bottom and a downwardly extending bucket back, means for pivoting said side plates together, and stop means on said side plates for the bucket back of the next above 65 element to engage with and thereby prevent

flexing of the excavator chain in one direction.

Des Moines, Iowa, May 14, 1930.
